US00D685654S

(12) **United States Design Patent**
Akana et al.

(10) **Patent No.:** US D685,654 S
(45) **Date of Patent:** ** Jul. 9, 2013

(54) **PACKAGING**

- (71) Applicant: **Apple Inc.**, Cupertino, CA (US)
- (72) Inventors: **Jody Akana**, San Francisco, CA (US); **Bartley K. Andre**, Menlo Park, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zorkendorfer**, San Francisco, CA (US)
- (73) Assignee: **Apple Inc.**, Cupertino, CA (US)
- (**) Term: **14 Years**
- (21) Appl. No.: **29/441,772**
- (22) Filed: **Jan. 9, 2013**

Related U.S. Application Data

- (63) Continuation of application No. 29/426,064, filed on Jun. 29, 2010, now Pat. No. 674,709, which is a continuation of application No. 29/363,816, filed on Jun. 15, 2010, now Pat. No. Des. 662,835, which is a continuation-in-part of application No. 29/354,604, filed on Jan. 26, 2010, now abandoned.

(57) **CLAIM**

The ornamental design for packaging, as shown and described.

DESCRIPTION

FIG. 1 is a front perspective view of packaging showing our new design;

FIG. 2 is a bottom perspective view thereof;

FIG. 3 is a front view thereof;

FIG. 4 is a rear view thereof;

FIG. 5 is a side view thereof;

FIG. 6 is another side view thereof;

FIG. 7 is a bottom view thereof; and,

FIG. 8 is a top plan view thereof.

The broken line portion of the figure drawings is included to show unclaimed subject matter only and forms no part of the claimed design.

1 Claim, 6 Drawing Sheets
